(57) **CLAIM**

The ornamental design for a mop head, as shown and described.

DESCRIPTION

FIG. 1 is a top plan view of a first embodiment of a mop head showing my new design;

FIG. 2 is a bottom plan view thereof;

FIG. 3 is a front elevation view thereof;

FIG. 4 is another elevation view thereof, rotated approximately 30 degrees;

FIG. 5 is another elevation view thereof, rotated approximately 60 degrees;

FIG. 6 is a top plan view of a second embodiment of a mop head showing my new design;

FIG. 7 is a bottom plan view thereof;

FIG. 8 is a front elevation view thereof;

FIG. 9 is another elevation view thereof, rotated approximately 30 degrees;

FIG. 10 is a top plan view of a third embodiment of a mop head showing my new design;

FIG. 11 is a bottom plan view thereof;

FIG. 12 is a front elevation view thereof; and,

FIG. 13 is another elevation view thereof, rotated approximately 15 degrees.

The background and shadows are environmental subject matter of the mop head and form no part of the claimed design.

1 Claim, 13 Drawing Sheets
